(57) **CLAIM**

We claim the ornamental design for the space shuttle mailbox, as shown and described.

DESCRIPTION

FIG. 1 is a front view of a space shuttle mailbox showing our new design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The broken lines shown in the drawings represent portions of the space shuttle mailbox that form no part of the claimed design.
